(57) **CLAIM**

The ornamental design for "television set," as shown and described.

DESCRIPTION

FIG. 1 is a top right front perspective view of the television set in accordance with our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; and,

FIG. 7 is a left side elevation view thereof.

Portions of the design shown in dashed lines form no part of the claimed subject matter.
